UNITED STATES PATENT OFFICE

109,495

DESIGN FOR AN AIR CLEANER

Alexander Marshall, Portland, Oreg.

Application September 14, 1937, Serial No. 71,613

Term of patent 14 years

To all whom it may concern:

Be it known that I, Alexander Marshall, a citizen of the United States, residing at Portland, in the county of Multnomah and State of Oregon, have invented a new, original, and ornamental Design for an Air Cleaner, of which the following is a specification, reference being had to the accompanying drawing, forming part thereof.

Figure 1 is a front perspective view of an air cleaner showing my new design;

Figure 2 is a side elevational view of the domi-

nant features of the design shown in Figure 1, and

Figure 3 is a top plan view of the cleaner shown in Figure 1.

The dominant features of my design reside in the portions shown in full lines.

I claim:

The ornamental design for an air cleaner, as shown and described.

ALEXANDER MARSHALL.
